COLLATOR FOR USE WITH
BURSTING MACHINEClarence L. Seibert, 18761 Newsom Ave., Cupertino,
and John Riepel, 383 S. 20th St., San Jose, Calif.Filed Mar. 2, 1964, Ser. No. 348,557
10 Claims. (Cl. 270—59)

The present invention relates in general to collators, and more particularly to a collator for use with a bursting machine.

High speed printing machines process continuously two-wide forms, which are numbered or lettered in predetermined series. For example, one side of the web may have consecutive even numbers printed thereon and the other side of the web may have consecutive odd numbers printed thereon.

As the continuous web advances through a bursting machine, the forms are cut down the middle. As the forms are ejected from the bursting machine, two forms emerge simultaneously side-by-side. This is a continuous process. Each pair of forms is burst into individual forms, one of which is consecutively numbered or lettered relative to the other.

An object of the present invention is to provide an improved collator for a bursting machine.

Another object of the present invention is to provide a collator for reducing mechanical failures.

Another object of the present invention is to provide a collator that has no operating moving parts for reducing service requirements arising out of mechanical failure during the operation thereof.

Another object of the present invention is to provide a collator that can be installed with facility and ease of operation.

Other and further objects and advantages of the present invention will be apparent to one skilled in the art from the following description taken in conjunction with the accompanying drawings, in which:

FIG. 1 is a perspective view of the collator of the present invention shown attached to a bursting machine.

FIG. 2 is an end elevation of the collator of the present invention looking toward the discharge end of the bursting machine and with parts thereof broken away to more clearly illustrate the configuration of the delay section.

It is conventional to have high speed printers or bursting machines that process continuously two-wide forms which have consecutive even numbers or letters in predetermined series printed down one side of the web or on one form and their complementary odd numbers or letters down the other side or on another form.

As the continuous web moves through the bursting machine, the margins are removed by slitting knives and a slitting unit also divides the form down the middle. As the forms are ejected from the bursting machine, two individual forms emerge simultaneously side-by-side. This is a continuous process. Each pair of forms is burst simultaneously as individual forms, one of which is consecutively numbered or lettered relative to the other.

According to the present invention, the collator 10 of the present invention is disposed at the discharge end of a bursting machine A to receive the simultaneously ejected side-by-side forms B and C. The collator 10 serves to speed the discharge of the form into a receptacle 11 and delay the discharge of the complementary form C into the receptacle 11, whereby in timed sequence the forms discharged from the bursting machine A will be arranged in a vertical stack in the receptacle 11 with the form C resting on its complementary form B, which was discharged simultaneously therewith, and with the form B resting on the form C that preceded it in being discharged from the bursting machine A.

2

Illustrated in FIG. 1 is the well-known bursting machine A. Disposed at the discharged end of the bursting machine A is the collator 10 of the present invention. The bursting machine A includes at its discharge end a platform 12 that is supported through angularly disposed rods 13 and 14. The rods 13 and 14 are anchored to the bursting machine A adjacent the discharge opening thereof. Formed in the platform 12 is a longitudinally extending slot 15.

The collator 10 rests or seats on the upper surface of the platform 12 through a floor or base 20 of the receptacle 11. When desired, the collator 10 may be adjustably secured to the platform 12 through a bolt and wing nut arrangement 21 that has the bolt received by the slot 15 and has the wing nut engaging the lower surface of the platform 12.

Spaced from the discharge end of the bursting machine A, the receptacle 11 includes an adjustably positioned rear wall or back stop 22. The back stop 22 includes an upstanding wall 23 that has a vertical slot 24 formed therein. In addition thereto, the back stop 22 includes an integrally formed, right-angle, horizontal base 25 that extends longitudinally toward the discharge end of the bursting machine A. The back stop base 25 is disposed below the base 20 of the receptacle 11 and has a longitudinally extended slot 26 formed therein.

For adjusting the effective length of the receptacle 11, the base 20 of the receptacle 11 has a suitable opening 30 therein. A bolt 29 is received by the opening 30 of the receptacle base 20, the slot 26 of the back stop base 25 and the slot 15 of the platform 12. A wing nut 31 is threaded on the bolt 29 and engages the lower surface of a washer 32, which in turn engages through its upper surface the lower surface of the platform 12. Thus, the nut 31 is loosened to permit the back stop 22 to be moved toward or away from the discharged end of the bursting machine A for adjusting the effective length of the receptacle 11. After the desired length is achieved for the receptacle 11, the nut 31 is tightened for securing the back stop 22 to the receptacle 11 and the rear end of receptacle 11 to the platform 12.

As shown in FIGS. 1 and 2, the receptacle 11 also includes an integrally formed side wall 35. Clamped to a transverse rod 36 of the burster machine A is a downwardly directed, longitudinally extending, yieldable, form engaging arm 37. Preferably, the arm 37 is formed from a leaf spring. At its proximal end, the arm 37 is anchored at the discharge end of the bursting machine A by means of a clamp 38 that is secured to the rod 36. The distal end of the arm 37 is received by the slot 24 of the back stop 22. The arm 37 is directed downwardly from the rod 36 toward the back stop 22.

When a form B is discharged from the bursting machine A, the form B advances below the yieldable arm 37 to be received by the receptacle 11. The arm 37 serves to guide the movement of the form B into the receptacle 11 and also to increase the speed of travel into the receptacle 11. As the vertical stack of forms in the receptacle 11 increases in height, the yieldable arm 37 is elevated therewith and tends to move toward a horizontal position.

Confronting the side wall 35 of the receptacle 11 and disposed adjacent the opposite side of the receptacle 11 is a form delay chute 40. The form delay chute 40 comprises an angularly disposed wall 41 that is inclined upwardly and outwardly with respect to the base 20 of the receptacle 11 and extends longitudinally along a side thereof. Joining the angularly disposed wall 41 is a longitudinally extending, horizontal wall 42 of the form delay chute 40. Continuing from the horizontal wall 42 is an upwardly and outwardly directed inclined wall 43 of the form delay chute 40. It is to be observed that the

angle of inclination for the wall 41 is greater than the angle of inclination of the wall 43 taken relative to the base 20 of the receptacle 11 or the horizontal wall 42. The wall 42 and the base 20 are parallel to one another.

Fixed to the end of the walls 41-43 in the vicinity of the back stop 22 is an end wall 44 of the form delay chute 40. The wall 44 is secured to the walls 41-43 by suitable means, such as rivets. At the opposite end of the form delay chute 40 is located an end wall 45, which is also secured to the walls 41-43 by rivets. Secured by screws to the end wall 45 is an upstanding post 46. Adjustably mounted on the post 46 is a form guide 47, which has a vertical slot 48 formed therein. Screws 49 adjustably secure the form guide 47 to the post 46 for regulating the height of the form guide 47. The height of the upright form guide 47 is slightly above the transverse rod 36. The form C, when discharged, passes over the form guide 47.

When the form C is discharged from the bursting machine A into the form delay chute 40, it is advancing in the direction of the end wall 44. As a consequence thereof, the form C at its leading end engages the wall 44 and at its lower surface contacts initially the walls 43 and 42. The impact of the form C with the end wall 44 causes the form C to change its direction of travel and advance sidewise toward the receptacle 11. In travelling sidewise, the form C slides down the wall 41 into the receptacle 11. As a result of the foregoing, the travel time for the form C to reach the receptacle 11 for stacking is greater than the travel time for the form B, ejected simultaneously therewith, to reach the receptacle 11 for stacking.

In the operation of the collator 10, forms B and C are ejected simultaneously from the bursting machine A. Form B falls directly into the receptacle 11 and the speed of travel therefor is increased by the action of the yieldable arm 37.

The form C is discharged into the form delay chute 40. As a consequence thereof, the leading end of the form C engages the wall 44 causing the form C to change its direction of travel. This results in the form C travelling sidewise toward the receptacle 11 and engaging in sliding contact the walls 43, 42 and 41. The form C is now stacked onto the form B. Both forms B and C are vertically stacked with the form C resting on the form B. The succeeding forms B and C are stacked in the same manner with the succeeding form B, however, resting on the preceding form C.

It is to be observed that the form C emerging from the bursting machine A is delayed by the form delay chute 40 through the action of the end wall 44 and the configuration of the walls 43, 42 and 41. This action allows proper timing to vertically stack the forms discharged by the bursting machine A in the proper sequence and consecutive order.

From the foregoing, it is noted that the collator 10 of the present invention has no moving parts and, hence, reduces service requirements arising out of wear and tear. Further, the collator 10 can be installed with facility and ease operation. The length and depth of the receptacle 11 can be altered to accommodate the size of form being collated.

It is to be understood that modifications and variations of the embodiment of the invention disclosed herein may be resorted to without departing from the spirit of the invention and the scope of the appended claims.

Having thus described our invention, what we claim as new and desire to protect by Letters Patent is:

1. A collator adapted for use with a bursting machine which discharges a plurality of forms simultaneously, said collator comprising a support, a receptacle on said support for receiving directly one of said forms, and a chute on said support disposed adjacent to said receptacle for receiving another of said forms, said chute comprising an upwardly directed flat wall stop disposed in the path

of travel of the leading end of said other form to stop the forward motion of said other form for changing the direction of travel of said other form to enable said chute to direct said other form sidewise into said receptacle for stacking said other form with said one form in a predetermined sequence.

2. A collator adapted for use with a bursting machine which discharges a plurality of forms simultaneously, said collator comprising a support, a receptacle on said support for receiving directly one of said forms, and a chute on said support disposed adjacent to said receptacle for receiving another of said forms, said chute comprising an upwardly directed flat wall stop disposed in the path of travel of the leading end of said other form to stop the forward motion of said other form for changing the direction of travel of said other form and a declining wall declining in a direction toward said receptacle for directing said other form in a sidewise movement into said receptacle and for supporting said other form in its sidewise movement toward said receptacle for stacking said other form with said one form in a timed sequence and in a predetermined order.

3. A collator adapted for use with a bursting machine which discharges a plurality of forms simultaneously, said collator comprising a support, a receptacle on said support for receiving directly one of said forms, a yieldable arm disposed above said receptacle for urging said one form directly into said receptacle, and a chute on said support disposed adjacent to said receptacle for receiving another of said forms, said chute comprising an upwardly directed wall stop disposed in the path of travel of the leading end of said other form to stop the forward motion of said other form for changing the direction of travel of said other form and a declining wall declining in a direction towards said receptacle for directing said other form in a sidewise movement into said receptacle and for supporting said other form in its sidewise movement towards said receptacle for stacking said other form with said one form in a timed sequence and in a predetermined order.

4. A stacker adapted for use with a bursting machine which discharges a plurality of forms, said stacker comprising a receptacle for receiving directly a form, said receptacle including an upright rear wall with a vertically disposed slot formed therein, a yieldable arm disposed above said receptacle with its free end received by said slot, said yieldable arm being arranged to urge a form into said receptacle, and means disposed adjacent to the forward end of said receptacle for supporting the proximal end of said yieldable arm.

5. A stacker adapted for use with a bursting machine which discharges a plurality of forms, said stacker comprising a receptacle for receiving directly a form, said receptacle including a base and an upright rear wall with a vertically disposed slot formed therein, means for adjustably securing said upright wall relative to said base for regulating the effective length of said receptacle, a yieldable arm disposed above said base with its free end received by said slot, said yieldable arm being arranged to urge a form into said receptacle, and means disposed adjacent to the forward end of said receptacle for supporting the proximal end of said yieldable arm.

6. A collator adapted for use with a bursting machine which discharges a plurality of forms simultaneously, said collator comprising a support, a receptacle on said support for receiving directly one of said forms, said receptacle including an upright rear wall with a vertically disposed slot formed therein, a yieldable arm disposed above said receptacle with its free end received by said slot, said yieldable arm being arranged to urge said one form into said receptacle, means disposed adjacent the forward end of said receptacle for receiving the proximal end of said yieldable arm, and a chute on said support disposed adjacent to said receptacle for receiving another of said forms, said chute comprising a wall stop

disposed in the path of travel of the leading end of said other form to stop the forward motion of said other form for changing the direction of travel of said other form and a declining wall declining in a direction toward said receptacle for directing said other form in a sidewise movement into said receptacle and for supporting said other form in its sidewise movement toward said receptacle for stacking said other form with said one form in a timed sequence and in a predetermined order.

7. A collator adapted for use with a bursting machine which discharges a plurality of forms simultaneously, said collator comprising a support, a receptacle on said support for receiving directly one of said forms, said receptacle including a base and an upright rear wall with a vertically disposed slot formed therein, means for adjustably securing said upright wall to said base for regulating the effective length of said receptacle, a yieldable arm disposed above said base with its free end received by said slot, said yieldable arm being arranged to urge said one form into said receptacle, means for supporting the proximal end of said yieldable arm, and a chute on said support disposed adjacent to said receptacle for receiving another of said forms, said chute comprising a wall stop disposed in the path of travel of the leading end of said other form to stop the forward motion of said other form for changing the direction of travel of said other form and a declining wall declining in a direction toward said receptacle for directing said other form in a sidewise movement into said receptacle and for supporting said other form in its sidewise movement toward said receptacle for stacking said other form with said one form in a timed sequence and in a predetermined order.

8. A collator adapted for use with a bursting machine which discharges a plurality of forms simultaneously, said collator comprising a support, a receptacle on said support for receiving directly one of said forms, said receptacle including a base and an upright rear wall with a vertically disposed slot formed therein, means for adjustably securing said upright wall to said base for regulating the effective length of said receptacle, a yieldable arm disposed above said base with its free end received by said slot, said yieldable arm being arranged to urge said one form into said receptacle, means for supporting the proximal end of said yieldable arm, a chute on said support disposed adjacent to said receptacle for receiving another of said forms, said chute comprising a wall stop disposed in the path of travel of the leading end of said other form to stop the forward motion of said other form for changing the direction of travel of said other form and a declining wall declining in a direction toward

said receptacle for directing said other form in a sidewise movement into said receptacle and for supporting said other form in its sidewise movement toward said receptacle for stacking said other form with said one form in a timed sequence and in a predetermined order, an upright post on said chute for guiding said other form into said chute, and means on said post for adjusting the effective height thereof.

9. A collator adapted for use with a bursting machine which discharges a plurality of forms simultaneously, said collator comprising a support, a receptacle on said support for receiving directly one of said forms, and a chute on said support disposed adjacent to said receptacle for receiving another of said forms, said chute comprising an upwardly directed flat wall stop disposed in the path of travel of the leading end of said other form to stop the forward motion of said other form for changing the direction of travel of said other form and a declining wall disposed at right angles to said upwardly directed flat wall stop and declining in a direction toward said receptacle for directing said other form in a sidewise movement into said receptacle and for supporting said other form in its sidewise movement toward said receptacle for stacking said other form with said one form in a timed sequence and in a predetermined order.

10. A collator adapted for use with a bursting machine which discharges a plurality of forms simultaneously, said collator comprising a support, a receptacle on said support for receiving directly one of said forms, and a chute on said support disposed adjacent to said receptacle for receiving another of said forms, said chute comprising an upwardly directed flat wall stop disposed in the path of travel of the leading end of said other form to stop the forward motion of said other form for changing the direction of travel of said other form and a step declining wall disposed at right angles to said upwardly directed flat wall stop and declining in a direction toward said receptacle for directing said other form in a sidewise movement into said receptacle and for supporting said other form in its sidewise movement toward said receptacle for stacking said other form with said one form in a timed sequence and in a predetermined order.
